UNITED STATES PATENT OFFICE

MICHAEL LIPTAK, OF ST. PAUL, MINNESOTA

MUD DRUM SEAL

Application filed November 30, 1931. Serial No. 578,010.

My present invention relates to boilers, and more particularly to boilers of the bent tube type wherein mud drums are hung from the tubes; and provides an extremely simple and highly efficient mud drum seal. Generally stated, the invention consists of the novel construction and arrangement of parts, in combination with the devices hereinafter described and defined in the claims.

10 In boilers of the above indicated type, the mud drums are hung below the upper drums or boilers proper and are connected thereto by a varied number of water tubes. These water tubes, because of their very lines and extent of expansion and contraction, tend to shift the mud drums transversely of their axis, that is, laterally upward and downward, and expansion in the drums will tend to produce axial movements of the ends or 20 head portions of the drums. When the ends of the drum are set into the furnace wall, against unyielding refractory blocks or material, the strain put upon the mud drum will frequently crack the unyielding refractories or strain the tubes and cause leaky joints between the tubes and mud drum. For these 30 reasons, it is necessary to provide a yielding packing or joint-forming structure that will also maintain a gas-tight joint between the ends of the mud drum and the furnace wall. Moreover, the ends of the mud drums and especially those that have riveted or welded joints, must be frequently inspected for defects, causing small leaks or which are 35 liable to cause leakage. Hence it becomes of the utmost importance that an arrangement be provided which will yield to movements of the mud drum and always maintain gas-tight joints between the furnace wall and drum 40 and which may be quickly removed for inspection purposes, and then quickly re-applied. Also such joints should have high heat insulating efficiency. Boiler explosions have been frequently caused by rivets weakened by corrosion and hence the imperative necessity for frequent inspection.

My present invention provides an extremely simple and highly efficient mud drum seal which has all of the above noted desirable features. Several commercial forms of this

improved mud drum seal are illustrated in the accompanying drawings, wherein like characters indicate like parts throughout the several views.

Referring to the drawings:

Fig. 1 is a somewhat diagrammatic vertical section showing the general arrangement of one type of boiler wherein the mud drum is suspended by tubes;

Fig. 2 is an elevation looking at the improved mud drum seal as applied to a furnace wall and to the end of the mud drum of a boiler, such as illustrated in Fig. 1;

Fig. 3 is a vertical section taken on the line 3-3 of Fig. 2;

Fig. 4 is a vertical section showing a tubular casing of the improved mud drum seal removed from working position;

Fig. 5 is a vertical section showing a retaining diaphragm removed from the tubular casing;

Fig. 6 is a vertical section showing a door plate to be used with but which is removed from the retaining diaphragm;

Fig. 7 is a fragmentary enlarged section taken on the same line as Fig. 3;

Fig. 8 is a section taken on the line 8-8 of Fig. 3;

Fig. 9 is a fragmentary view in elevation illustrating a slightly modified form of the door plate used in connection with a retaining diaphragm;

Fig. 10 is a view corresponding to Fig. 3 illustrating a somewhat modified form of the mud drum seal;

Fig. 11 is a vertical axial section showing a tubular casing of the structure illustrated in Fig. 10, removed from working position;

Fig. 12 is an enlarged fragmentary section taken on the same line as Fig. 10;

Fig. 13 is another view corresponding to Fig. 3, but illustrating a still further modified form of an application of the invention;

Fig. 14 is another view corresponding to Fig. 3, but illustrating a still further modified form of the invention;

Fig. 15 is an elevation looking at the inner face of the removable retaining diaphragm;

Fig. 16 is an elevation looking at the outer face of the retaining diaphragm; and

Fig. 17 is a fragmentary section taken on the line 17—17 of Fig. 15.

Referring to the construction illustrated in Figs. 1 to 8, inclusive, and directing attention first particularly to Fig. 1, the numeral 20 indicates the furnace walls, the numerals 21 and 22 the upper boiler drums, the numerals 23 and 24, the lower or mud drums, and the numeral 25 the boiler tubes, and which parts are of the very well known arrangement in boiler installations of the bent tube type. The flexible mounting which forms the mud drum seal, in accordance with my invention, is particularly illustrated as applied to the mud drum 23 and which mud drum has heads 23^a secured thereto in telescoped arrangement by rivets 23^b. It is leakage that occurs when rivets 23, either because of defective workmanship or because of corrosion, cause the greatest trouble in maintaining boiler drums in working condition; and hence State laws or rules established by insurance companies make it imperative that these joints should be frequently inspected by persons authorized to do so. Insurance companies have refused to carry insurance on boilers unless inspection could be made of the above noted riveted joints, and in many instances, this has required tearing out of a large area of the furnace walls.

My invention makes the above noted inspection a very simple and easy matter and, moreover, makes repair of bad rivets possible without removing more than a small part of the surrounding furnace wall.

In building up the furnace wall 20, adjacent the end of the mud drum, settle blocks 26 and 27 which have concave upper surfaces are built into the furnace wall with their concave surfaces spaced from but concentric with but both radially and axially outward of the end of the mud drum or boiler. These settle blocks form a sort of saddle on which is laid, throughout that segmental zone represented by the concave upper surfaces of said settle blocks, the lower members of an outer ring of bricks 28 and the lower members of an inner ring of bricks 29. The bricks 28 may be common brick but the inner bricks 29 must be refractory tile and also the settle blocks 26 are advisably refractory tile. The settle blocks form a sort of a saddle upon which the lower zone or segment of the rings of bricks 28 and 29 are laid, and the bricks 28 and 29 thus primarily laid, have their inner surfaces concentric with but radially outward from the outer cylindrical surface of the drum 23, and they in turn afford a sort of saddle on which is placed a cylindrical or tubular metal casing 30. The casing 30 when thus positioned, will be concentric with but spaced radially outward from the outer surface of the drum

23, and it then affords a templet or form around which the further bricks 28 and 29 will be laid to complete the rings or annular series of bricks 28 and 29. Here it will be noted that the inner bricks 29 at their inner ends are formed with enlargements 29^a that project radially toward the drum 23 but are spaced therefrom at points inward of the rivets 23^b.

It will also be noted by reference particularly to Fig. 3, that the space between the outer heads of the rivets 23^b and the bodies of the bricks 29 is approximately the same as the space between the inner surfaces of the portions 29^a and the outer surface of the drum. Further, it should be here noted that the metal casing 30 when positioned as described in this preferred arrangement, is located with its inner edge in a plane that is outward of the plane of the rivets 23^b. The importance of this latter noted arrangement will appear later on.

The numeral 31 indicates a metal diaphragm or annular retaining plate that fits within the casing 30 and is detachably secured thereto by suitable means. In this particular illustration, a rolled annular commercial angle bar 32 is permanently secured to the interior of the casing 30 by suitable means such as rivets 33, and the diaphragm 31 is arranged to be secured to the inward projecting flange of said angle 32 by suitable means such as cap screws 34. The central opening of the annular diaphragm 31 is arranged to be closed by a door plate or cover 35 that is provided with an inwardly projecting annular flange 36 that telescopes through the opening of said diaphragm and when in position, comes close to the drum head 23^a. As means for detachably securing the door plate 35 to the diaphragm 31, the latter is shown as provided with outwardly projecting studs 37 engageable through perforations 38 in the flange of the door plate 35 and provided with nuts 39. Also door plate 35 is shown as provided with a handle 40.

The space between the mud drum and the adjacent bricks 29, casing 30 and diaphragm 31 is filled in with a more or less fibrous, highly refractory material such as asbestos cement, mineral wool or the like, indicated by the character *a*. The same or similar insulating material *b* is preferably filled into the panel like structure afforded by the door plate 35 and its flange 36.

Some of the insulating packing will be packed in between the mud drum and the bricks 29 and inner portion of the casing 30 before the diaphragm 31 has been applied, and after the diaphragm has been applied, the rest of the material *a* will be tightly packed in up to the inner edge of said diaphragm. The contraction between the lugs or projecting portions 29^a of the bricks 29,

cause the packing to be tightly contracted around the riveted heads and against the drum, but the arrangement leaves sufficient thickness of the pliable insulating material 5 surrounding the drum and rivets to permit all the movements of the mud drum that will take place under expansion and contraction. When the door plate has been applied with its insulating material *b*, the central portion 10 of the mud drum head is also well insulated against radiation of heat.

When inspection of the riveted joints is necessary, the diaphragm will be removed and the pliable insulating material may be 15 quickly and easily removed and when this is done, a clear vision of the outer rivet heads and the riveted joint is afforded. After the inspection has been made, if the joints are found to be in good condition, the insulating 20 material may be quickly repacked and the diaphragm quickly replaced in working position. As is obvious, the tightly packed insulating material in addition to being pliable or flexible, forms a gas-tight joint against 25 leakage of gases from the furnace. If a defective joint or defective rivets are found, repairs can be made quite easily.

For example, if a leaky rivet is found, a few of the blocks of the furnace wall will be 30 removed from the zone in the immediate vicinity of the rivet and a repair tool or tools may be brought into contact with the rivet without removing the metallic casing 30. Here will be noted the importance of having 35 the inner edge of the casing 30 outward of the plane of the rivets, so that the rivets can be reached through the space afforded by removal of a few of the wall bricks. The casing 30 is thus left in position so that the 40 removed wall blocks may be properly and quickly replaced after the repair has been made. It is also important to note that the metallic casing 30, in addition to forming a templet, for initial laying of bricks, affords 45 a support that keeps the wall bricks or elements surrounding the drum from falling upon or coming too close to the drum and its head, even if the furnace wall should be cracked due to expansion and contraction 50 under the long continued usage.

It is important also to note that the inner bricks 29 are of such length that they project well over onto the casing 30 and hence will be definitely positioned thereby. It is 55 further important to note that the angle bar or flange 32 gives the metal casing 30 very great rigidity and strength to resist a crushing action and to keep the casing in true cylindrical form, not only when positioned, but 60 during shipment or handling.

In the construction illustrated in Figs. 10, 11 and 12, the drum head 23^a is of the type provided with a man-hole 23^c normally closed by a suitable man-hole cover 41. In 65 this arrangement, the metal casing 30^a is

shown as extended to the plane of the rivets 23^b, and is provided on its inner surface with circumferentially spaced inwardly projecting angle lugs 42 secured thereto by nut-equipped bolts; and the annular diaphragm 31^a is shown as set in and of such internal diameter that it will closely engage the drum head 23^a.

In this instance, the diaphragm 31^a is 75 shown as detachably secured to the lugs 42 by cap screws 44. This diaphragm 31^a and preferably also the diaphragm 31 before described, are of quite thin sheet steel and hence have sufficient resilience to adapt themselves to movements of the drum head caused by expansion and contraction.

The modified structure illustrated in Fig. 13 is much like that illustrated in Fig. 10, but in this arrangement, the annular diaphragm 31^b is provided at its inner edge with an annular angle flange 45 rigidly secured thereto, with its inner edge extending close to or even in engagement with the drum head. As shown, the angle flange 45 is detachably secured to diaphragm 31^b by nut-equipped studs 46. When this angle flange 45 is removed the insulating material *a* can be 85 packed into the space provided therefor partly before the diaphragm is applied and the remainder after the diaphragm has been applied, and such material will be held in place when the angle flange is applied to the diaphragm.

The construction illustrated in Figs. 14, 15 and 16 and 17, provides a flexible gas-tight joint with a minimum amount of packing, and which affords an inspection with a minimum of work. In this arrangement, the metal casing 30^b is provided with an internal angle flange 47 bolted or otherwise rigidly secured thereto, and the annular diaphragm 31^c is provided at its outer edge with an inwardly projecting angle flange 48, bolted or otherwise rigidly secured thereto, and at its inner edge with an inwardly projecting angle flange 49. Said diaphragm 31^c is detachably secured to the angle flange 47 by machine screws 50 and when in working position, the inner flange of the angle flange 49 will come 100 close to the drum head 23^a surrounding its man-hole 23^c.

The pliable insulating packing *a*¹ is packed between the drum and the surrounding portion of the casing 30^b and lugs 29^a of bricks 29. Further pliable insulating material *a*² is packed into the pan-like structure afforded by the diaphragm 31^c and its flanges 48 and 49; and to assist in holding this packing *a*² in position, radial rods 51 are extended between the inner portions of the angle flanges 48 and 49. With this arrangement, the insulating material *a*² is applied to the diaphragm before the latter has been applied in working position and, of course, will be 110 removed therewith when the diaphragm is 120 125 130

removed for inspection purposes. This arrangement leaves a heat-insulating air space between the insulating packings a^1 and a^2 . Obviously, inspection may be very quickly made with this arrangement for the reason that it is only necessary to remove the diaphragm and the small amount of packing a^1 . Diaphragm 31^c is shown as provided with hand grips 52.

- 10 The door plate illustrated in Fig. 9 is especially adapted for use in connection with a structure such as shown in Fig. 13, but may be used wherever desired. This door plate indicated by the numeral 53 is shown as connected to the diaphragm 31^b by hinges 54, and is arranged to be locked to said plate in closed position by nut-equipped clamp 55.

From the foregoing it is evident that the device described is capable of various modifications within the scope of the invention herein disclosed and claimed. The process employed in this erection of the device described is not herein claimed, but is made the subject-matter of a companion application filed of even date herewith and entitled "Process of erecting mud drum seals".

What I claim is:

1. In a mud drum seal, a tubular casing adapted to be embedded in a furnace wall 20 concentric to and in the vicinity of the head of the mud drum, a diaphragm removably secured to said casing, and an insulating packing adapted to be packed within said casing and against the mud drum and to be held in place by said diaphragm.

2. In a mud drum seal, a tubular casing adapted to be embedded in a furnace wall concentric to and in the vicinity of the head of the mud drum, a diaphragm removably secured to said casing, an insulating packing adapted to be packed within said casing and against the mud drum and to be held in place by said diaphragm, said diaphragm having a central opening, and a door plate normally closing said central opening but movable to open the same.

3. In a mud drum seal, a tubular casing adapted to be embedded in a furnace wall concentric to and in the vicinity of the head of the mud drum, a diaphragm removably secured to said casing, an insulating packing adapted to be packed within said casing and against the mud drum and to be held in place by said diaphragm, said diaphragm having a central opening, and a door plate normally closing said central opening but movable to open the same, said door plate having an annular flange projecting through the opening of said diaphragm.

4. In a mud drum seal, a tubular casing adapted to be embedded in a furnace wall concentric to and in the vicinity of the head of the mud drum, a diaphragm removably secured to said casing, an insulating packing 65 adapted to be packed within said casing and

against the mud drum and to be held in place by said diaphragm, said diaphragm having a central opening, and a door plate normally closing said central opening but movable to open the same, said door plate having an annular flange projecting through the opening of said diaphragm and further having a handle projecting from its outer face.

5. The combination with a furnace wall 75 and a boiler drum having its head end extended into an opening in said wall, of a tubular metal casing of greater diameter than said drum set into said wall surrounding the head thereof, a diaphragm detachably secured to said casing, and a refractory packing held against the head end of the drum by said casing and diaphragm, said diaphragm and packing, when removed, affording access to the drum head for inspection thereof.

6. The structure defined in claim 5 in which said drum has a head secured thereto by rivets and in which said metal casing at its inner edge terminates outward of the plane of the boiler rivets so that access to the rivets may be had when a limited zone of the furnace wall is removed.

7. The structure defined in claim 5 in further combination with settle blocks built into the furnace wall and having concave surfaces that are concentric to said casing.

8. The structure defined in claim 5 in further combination with settle blocks built into the furnace wall and having concave surfaces that are concentric to said casing, and a ring of bricks built into the furnace wall immediately surrounding said casing, certain of said bricks being directly laid upon the concave surfaces of said settle blocks.

9. The structure defined in claim 5 in further combination with a ring of bricks built into the furnace wall immediately surrounding said casing.

10. The structure defined in claim 5 in further combination with a ring of bricks built into the furnace wall immediately surrounding said casing, the inner of the ring-forming bricks having inwardly projected inner end portions that approach more closely to the drum than the body portions of said ring-forming bricks.

11. The structure defined in claim 5 in further combination with a ring of bricks built into the furnace wall immediately surrounding said casing, the inner of the ring-forming bricks having inwardly projected inner end portions that approach more closely to the drum than the body portions of said ring-forming bricks, said drum having a head secured thereto by rivets, the said rivets being in a plane that is outward of the inwardly extended inner end portions of said inner ring-forming bricks.

12. The structure defined in claim 5 in

1. further combination with a ring of bricks built into the furnace wall immediately surrounding said casing, the inner of the ring-forming bricks having inwardly projected 5 inner end portions that approach more closely to the drum than the body portions of said ring-forming bricks, said drum having a head secured thereto by rivets, the said rivets being in a plane that is outward of the 10 inwardly extended inner end portions of said inner ring-forming bricks, the inner edge of said casing being in a plane outward of the plane of said boiler rivets.
2. The structure defined in claim 5 in 15 which said tubular casing is provided with a rigidly secured internal angle flange to which said diaphragm is detachably secured.
3. The structure defined in claim 5 in 20 which said tubular casing is provided with a rigidly secured internal angle flange to which said diaphragm is detachably secured, said diaphragm having a central opening, and a door plate rigidly secured to said diaphragm and normally closing the opening 25 thereof, said door plate having an inwardly projecting annular flange.
4. The combination with a furnace wall and a boiler drum having its head end extended into an opening in said wall, of a 30 tubular metal casing of greater diameter than said drum set into said wall surrounding the head thereof, a diaphragm detachably secured to said casing, a refractory packing held against the head end of the 35 drum by said casing and diaphragm, said diaphragm and packing, when removed, affording access to the drum head for inspection thereof, a ring of bricks built immediately around said casing, and settle blocks 40 built into the furnace wall and having concave surfaces concentric to said casing and affording a saddle positioning the lower bricks of said ring.
5. The structure defined in claim 15 in 45 which said ring of bricks includes outer and inner bricks, the inner bricks projecting inward of the inner edge of said casing and said inner brick ends having portions projecting radially toward but spaced from the 50 drum.
6. The structure defined in claim 15 in 55 which said ring of bricks includes outer and inner bricks, the inner bricks projecting inward of the inner edge of said casing and said inner brick ends having portions projecting radially toward but spaced from the 60 drum, said drum having a head secured thereto by rivets located in a plane that is axially outward of the inwardly projected inner portions of the inner bricks of said ring.
7. The combination with a furnace wall and a boiler, said wall having a transverse opening of greater diameter than said boiler and into one end of which the adjacent end 65 of the boiler is extended, a diaphragm nor- mally closing the other end of said opening, means detachably securing the dia- phragm to the wall adjacent said other end of said opening, and a packing in the space between said diaphragm, the end of said boil- er and the wall of said opening, said open- ing, when said diaphragm and packing are removed, exposing the entire end of the boiler for inspection.
8. In testimony whereof I affix my signature. 75
MICHAEL LIPTAK.
